Attorney

UNITED STATES PATENT OFFICE

ALFRED SCHWARZ, OF UPPER MONTCLAIR, NEW JERSEY

SAFETY RAZOR.

Application filed March 26, 1930. Serial No. 439,021.

My invention relates to safety razors and more particularly has reference to the combination with safety razor mountings of magnetic reconditioning means for the razor blades.

It is known that a razor blade does not present a uniform cutting edge when examined under the microscope but that the edge consists of a multiplicity of very small and fine teeth which are very sensitive and readily distorted. It has heretofore been proposed to recondition the edges of the blade by contact with a magnet, the fine metallic particles of the blade being thereby re-aligned in accordance with the magnetic lines of force and the cutting edge thereby rendered more efficient. However, treatment of razor blades in this manner has necessitated the removal of the blade from the razor mounting or holder and has required the use of a magnetic conditioning device apart from the razor mounting.

It is accordingly an object of my invention to provide in a razor mounting a magnetic device so positioned as to recondition one of the cutting edges of a double edge blade while the other edge is exposed for use.

A more specific object of my invention resides in the provision of a razor mounting adapted to hold two or more double edge blades and so constructed as to magnetically recondition certain of the cutting edges while at least two cutting edges are exposed for use.

Other objects and advantages of my invention will appear from the more detailed description thereof.

I have found that, in order to properly recondition a razor blade magnetically, it is essential that the magnet be positioned directly under the cutting edge for otherwise the magnetic lines of force pull the fine metal particles in all directions and do not properly align the microscopic teeth of the cutting edge. Accordingly, in the construction of my improved razor mounting, the magnet is disposed directly under the edge of the blade which is not exposed for use.

For a more detailed understanding of my invention reference will be had to the accompanying drawings in which

Fig. 1 is an end view of a razor mounting containing two separate blades;

Fig. 2 is a front view, partly in section, of the razor mounting shown in Fig. 1;

Fig. 3 is a bottom plan view of the razor 55 mounting showing the blades in dotted lines;

Fig. 4 is a sectional view on the line 4—4 of Fig. 2; and

Fig. 5 is a sectional view of the line 5—5 of Fig. 1.

Referring more particularly to the drawings, the razor handle is indicated at 10 and may constitute the magnet for reconditioning the blades, being formed of magnetic iron which has been properly magnetized. 65 Base plate 11 has a longitudinal slot centrally thereof to snugly receive the enlarged upper end 12 of the magnetic handle which presents a magnetic surface for contact with the blades. Top plate 13 of the razor mounting is provided with the usual projections or lugs 14 extending through corresponding openings in base plate 11 as shown. A stem 15, which may be either cylindrical or rectangular, as shown, is fixed to or integral with top plate 13 and extends through slot 16 in handle 10, the lower end of stem 15 being provided with a threaded projection 17 adapted to receive nut 18 for holding the complete assembly together. 80

Razor blades 19 and 20, provided with suitable perforations or slots 21 to fit between lugs 14, are supported between the top and bottom plates on opposite sides of the razor mounting. By reason of the construction illustrated, it will be seen that the inner cutting edges 22 of the blades rest upon and are disposed directly over magnetic surface 12 while the opposite cutting edges 23 are exposed for use. 85

From the foregoing it will be apparent that my razor mounting at all times presents two cutting edges exposed for use while two other cutting edges are being simultaneously subjected to magnetic reconditioning by contact with magnetic surface 12, the magnet being disposed directly under the cutting edges to give a higher degree of reconditioning than is obtainable by otherwise positioning the blade with respect to the magnet, as above 90 100

explained. When cutting edges 23 have become dull by use, the position of the blades is reversed to expose edges 22 for use and to subject edges 23 to magnetic treatment by 5 contact with magnet 12, such reversal being repeated indefinitely.

It will therefore be seen that I have devised a razor mounting adapted to alternately recondition the opposite edges of a blade or 10 blades while retained in the mounting and without requiring the use of additional apparatus apart from the razor.

Although I have shown and described a preferred embodiment of my device, the invention is not to be construed as limited thereto as various changes and modifications 15 may be made therein without departing from the spirit and scope of my invention. For example, the handle 10 need not necessarily constitute the magnet, it being only essential that the temporarily unused cutting edges be directly exposed to magnetic action. Also the invention is not limited to the use of two blades as the device will be operative and useful 20 with only one blade and with only slight modification the mounting may be made to hold three or more blades. Accordingly, the invention is to be construed as limited only by the scope of the appended claims.

30 Having described my invention, I claim:
1. A razor mounting comprising a bottom guard plate, a magnet disposed centrally of said plate, a top plate, and means for retaining a pair of razor blades between said plates 35 with one blade on each side of and overlapping said magnet.

2. A safety razor comprising top and bottom guard plates, a magnet separable from said top and bottom plates disposed centrally 40 of said plates, and a pair of razor blades each having two cutting edges retained between said plates on opposite sides of said magnet, said magnet being in contact with the inner edge of each of said blades.

45 3. A razor mounting comprising top and bottom guard plates, an aperture in said bottom plate, a magnetic handle extending through said aperture, and means for retaining a double edge razor blade between said plates with one edge thereof in contact with 50 said handle and the other edge thereof exposed for use.

55 4. A razor mounting comprising top and bottom guard plates, an aperture centrally of said bottom plate, a magnetic handle extending through said aperture, and means for retaining a double edge razor blade between said plates on each side of said aperture with one edge of each blade in contact 60 with said handle and the other edge thereof exposed for use.

65 5. A safety razor comprising top and bottom guard plates, an elongated aperture in said bottom plate, a double edge razor blade retained between said plates with one edge

thereof exposed for use and the other edge disposed over said aperture, and a magnet supported in said aperture directly beneath said other edge of the blade, said aperture and magnet being of a length at least substantially equal to that of the blade. 70

6. A safety razor comprising top and bottom guard plates, an elongated aperture centrally of said bottom plate, a double edge razor blade retained between said plates on each side of said aperture with one edge of each blade exposed for use and the other edge thereof disposed over said aperture, and a magnet supported in said aperture directly beneath said other edge of each blade, said aperture and magnet being of a length at least substantially equal to that of the blades. 75

7. A razor mounting comprising top and bottom guard plates, an elongated aperture in said bottom plate, a magnet disposed in said aperture, and means for retaining a double edge razor blade between said plates with one edge thereof exposed for use and the other edge thereof directly over said magnet. 80

8. A razor mounting comprising top and bottom guard plates, an elongated aperture centrally of said bottom plate, a magnet disposed in said aperture, and means for retaining a pair of double edge razor blades between said plates with one blade on each side of said aperture and with one edge of each blade exposed for use and the other edge of each blade directly over said magnet. 85

90 In testimony whereof, I affix my signature. 100
ALFRED SCHWARZ.
